UNITED STATES PATENT OFFICE.

THOMAS CASSON, OF LONDON, ENGLAND.

SOLO ATTACHMENT FOR MUSICAL INSTRUMENTS.

SPECIFICATION forming part of Letters Patent No. 678,718, dated July 16, 1901.

Application filed August 2, 1900. Serial No. 26,675. (No model.)

To all whom it may concern:

Be it known that I, THOMAS CASSON, a citizen of England, residing at 19 Manor Mansions, Belsize Grove, London, England, have 5 invented certain new and useful Improvements in Melody Attachments for Musical Instruments, (for which I have applied for a patent in Great Britain, dated July 11, 1900, No. 12,509,) of which the following is a specification.

In instruments of the nature of the pianoforte having strings struck either directly or through intermediate mechanism by pneumatic levers operated by wind-pressure, also 15 in instruments having reeds sounded directly by wind, it is often desirable when a number of notes constituting harmony are played to emphasize the melody by causing the highest note of the treble harmony or the lowest 20 note of the bass harmony, or both of them, to sound louder than the other notes of the harmony.

My invention relates to means of effecting this as I shall describe, referring to the accompanying drawings, which show the application of my invention to the operation of pneumatic levers, which may act upon strings like those of a pianoforte.

Figure 1 is a transverse section on the line 1 1 of Fig. 2, which is a part-sectional plan on the line 2 2 of Fig. 1. Fig. 3 is a part-sectional plan on the line 3 3 of Fig. 1 of apparatus according to my invention for emphasizing the highest notes of a treble harmony.

35 *a* is one of a range of pneumatic levers arranged in any known manner to act upon a hammer or key of a pianoforte-action. *a* is charged with wind from the chamber *u*, when by pulling down the rod *c* the valve *b* is opened 40 and the valves *e* and *h* are closed, and when the rod *c* is allowed to rise the valve *b* is closed and the valve *e* opens to discharge the contents of *a*.

The rods *c* for the range of pneumatic levers may be moved by studs on barrels or on 45 boards by cam-levers passing through perforations in sheets or by pneumatic motors actuated by perforated sheets or otherwise. For reeds the rod *c* may be similarly moved 50 or by finger-key action.

The chamber *u* forms part of a note-to-note conduit, the chamber for each note commu-

nicating with that for the next lower note through an inclined passage *l*, so that wind admitted by a duct *d* to the chamber *u* of the 55 highest note when the valves *h* are open, as they usually are, can pass down through the hole *f* to *l*, thence up through the hole *g* to the chamber *u* of the next lower note, and so on throughout the whole range of treble notes. 60 When the rod descends, the valve *h* closes the hole *f*, shutting off the chamber *l*, and consequently the chamber *u* of the next lower note which communicates with *l* through the hole *g*. Thus the closing of any valve *h* cuts 65 off the chambers *u* of all lower notes from communication with its chamber *u*, and therefore from communication with the duct *d*. Thus the wind from *d* supplies only the motor of the highest note that is sounded by 70 pulling down the rod *c*. A tappet on the rod *c* acting on a lever in the chamber *l* lifts a valve *m*, opening a hole to a continuous conduit *n*, which is supplied with wind of suitable pressure for playing harmony, while the 75 duct *d* is supplied with wind of higher pressure for emphasizing the melody. As the valves *m* are all free to rise, wind of the lower pressure can always pass them from *n* into the chambers *l* and chambers *u* to 80 sound the lower notes of the harmony, while at the same time the highest note of the harmony is sounded by wind of the higher pressure from *d*, all the chambers *l* and *u* belonging to the lower notes being cut off from the 85 high-pressure air by the closing of the valve *h* of the highest note. As the closing of any valve *h* is accompanied by the opening of *m*, all the chambers *l* are thus cut off, which, until the closing of *h* may have in them wind 90 of the higher pressure, have that pressure at once reduced, as the wind can pass by the opened valve *m* to the conduit *n*, containing wind of lower pressure.

When the bass melody has to be emphasized, the chambers *l* have to be oppositely inclined and the wind of higher pressure is supplied to the chamber *u* of the lowest bass note, so that the lowest note of the bass harmony is sounded by the wind of higher pressure.

Although I have described the pneumatic levers as being distended by air under pressure, arrangements of ducts like those above

described with suitable inversions of valves might be employed for causing collapse of the pneumatic levers by vacuum, the rarefaction for the highest notes of the treble harmony or for the lowest of the bass harmony being greater than that for the other notes, so as to produce the desired emphasis. Suitable inversions of valves may also be used for collapse by exhaust of pneumatic levers ⁵ ₁₀ closed under pressure, the levers for the harmony discharging into a channel equivalent to *n* charged with wind of lower pressure than that surrounding the pneumatic levers, which are thus choked in their exhaust, and ₁₅ consequently move less energetically than the pneumatic lever of the emphasized note which has free exhaust. For emphasizing the melody in a reed instrument the same arrangement of chambers ²⁰ ₂₀ and their communications is employed; but the pneumatic levers *a* and discharge-valves *e* are dispensed with, the holes covered by *e* being permanently closed and the wind which passes the opened valves *b* going directly to ²⁵ the reeds. Suitable inversions of the valves would be employed for reeds blown by suction.

Having now particularly described the nature of my said invention and the best means I know of carrying the same into practical ³⁰ effect, I claim—

In a pneumatically - operated musical instrument, the combination with the chambers *u*, and ducts *l* arranged alternately in series and having communicating passages there- ³⁵ between, of two air-pressure conduits, one of which communicates with one of said chambers and the other with all of said ducts, said conduits supplying air of different pressures, means whereby several of said chambers may ⁴⁰ be opened at the same time to their respective pneumatics, and valves for cutting off all but one of said opened chambers from one of said conduits and valves for establishing communication between the remaining opened ⁴⁵ chambers and the other conduit, substantially as described.

In testimony whereof I have hereunto set my hand in presence of two subscribing witnesses.

THOMAS CASSON.
